SLACK OR CUTTINGS REMOVING
ATTACHMENTEdward J. Doberstein, Blue Island, Ill., assignor
to Goodman Manufacturing Company, Chicago,
Ill., a corporation of Illinois

Application November 19, 1941, Serial No. 419,690

11 Claims. (Cl. 262—30)

This invention relates to improvements in slack or cuttings removing attachments for kerf-cutting machines of the room and pillar type, and has as its principal objects to provide a relatively light cuttings removing device of the class described, readily attachable to and adapted to extend either rearwardly beyond or laterally from a kerf-cutting machine of standard construction, together with a power drive connection from the machine when in either of these positions.

In coal cutting machines in use today, the cutter bar lengths and feeding speeds of the machines have been increased over those formerly used, in order to increase the capacity of the machine, with the result that the slack discharged by the cutter chain of the machine is more than can be handled by a man shoveling by hand. While conveyers have been provided to discharge the cuttings to the rear of the machine, it has been difficult to place the conveyer so it will efficiently collect the slack, and the conveyer is of little or no use where roof conditions are poor and it is necessary to post timbers close to the working face. In carrying out my invention, I remedy this difficulty by providing an improved form of cuttings passageway arranged to permit the cutter chain to readily propel the cuttings therealong in a confined path, to the rear end of the machine, and by providing a cuttings deflector arranged to deflect the cuttings onto a cuttings discharge conveyer in cuttings-receiving relation with respect to said deflector. I also arrange the cuttings discharge conveyer so it may extend longitudinally rearwardly from the machine, for discharging the cuttings into a face conveyer, if desired; or so it may extend laterally from the machine, where roof conditions are poor and it is necessary to post props close to the working face. The arrangement is such that the conveyer may collect the cuttings as efficiently when in one position as in the other.

Other objects of my invention will appear from time to time as the following specification proceeds and with reference to the accompanying drawings wherein:

Figure 1 is a fragmentary plan view of a kerf-cutting machine of the room and pillar type, with a cuttings removal device constructed in accordance with my invention attached thereto and shown as extending rearwardly beyond the rear end thereof;

Figure 2 is a fragmentary view in side elevation of the device shown in Figure 1, with certain parts shown in longitudinal section;

Figure 3 is an enlarged plan view of the rear

part of the machine, with certain parts removed and showing the cuttings removing device as extending laterally from the machine, for discharging cuttings towards the retreating side thereof;

5 Figure 4 is an enlarged fragmentary transverse sectional view taken substantially along line 4—4 of Figure 1;

Figure 5 is an enlarged fragmentary transverse sectional view taken substantially along line 5—5 of Figure 1;

10 Figure 6 is a detail view, showing certain details of the means for connecting the cuttings removal conveyer to the machine;

Figure 7 is an enlarged detail view showing certain details of the drive to the cuttings removal conveyer;

15 Figure 8 is an enlarged detail longitudinal sectional view, showing certain details of the drive to the cuttings removal conveyer; and

20 Figure 9 is an enlarged detail fragmentary plan view, showing the drive to the cuttings removal conveyer in a different position than in Figure 8.

Referring now to the details of the embodiment of my invention illustrated in the drawings, 25 a slack-removing conveyer generally indicated by reference character 10 is shown as connected to the discharge end of a kerf-cutting machine 11 of a well known construction and operation. Said machine consists of a main frame 12 having a cutter bar 13 projecting forwardly from the forward end thereof. Said cutter bar has a cutter chain 14 guided for orbital movement thereabout and operates in a channel formed between the bottom of said main frame and the base plate 15. Said cutter chain is driven from a cutter chain drive sprocket 16, mounted on the lower end of a vertical shaft 17, suitably journaled in said main frame, and driven from a motor 18 on said main frame. The drive from said motor to said sprocket includes a spur gear reduction 19, a bevel pinion 20 on a longitudinal shaft 21, and a bevel gear 23 meshed with said pinion and mounted coaxially with said vertical shaft.

45 A flexible feeding means is provided for moving the machine about the mine and sumping the cutter bar 13 and cutter chain 14 into the coal face and moving said bar and chain thereacross. Said flexible feeding means may be of any usual construction but, as herein shown, comprises a winding drum 24 on the advance side of the machine and having a flexible cable 25 adapted to be wound thereon and be anchored at suitable points along the working face, to feed the cutter bar into and across the coal face.

50 Referring now in particular to the details of

the slack removing conveyer 10, which forms the subject matter of the present invention, said conveyer consists of an elongated conveyer frame 29 of a generally trough-like form and having a generally horizontal cuttings receiving portion 30 and an inclined elevating discharge portion 31 extending rearwardly therefrom. The frame 29 carries a pair of endless conveyer chains 32, 32 with flights 33, 33 mounted therebetween, movable upwardly along a bottom plate 34 of said frame.

The horizontal cuttings receiving portion of said frame is detachably connected to the rear end of the machine so as to extend longitudinally rearwardly therefrom, for discharging cuttings to the rear of the machine, or laterally from the machine for discharging cuttings beyond the retreating side of the machine. A deflecting member 35 extends across the rear end of the base plate 15 and along one side of the receiving portion of the cuttings collecting conveyer 10, and besides forming a means for guiding and deflecting the cuttings onto two sides of the receiving end of said conveyer, also forms a means for connecting one side of the conveyer to the machine. As herein shown, said cuttings deflecting member is of a substantially L-shaped formation, secured to and projecting rearwardly from the rear end of the base plate 15, and is provided with a laterally extending portion 36 which extends across the rear end of said base plate and is curved to conform to the path of the cutter chain. Said laterally extending portion is also curved upwardly from the bottom of said base plate to the plane of the receiving portion of the conveyer 10, for elevating and guiding the cuttings onto the side of the conveyer which extends across the rear end of the machine. Said deflecting member also has a rearwardly extending curved upright deflecting wall 37 leading from a trough-like bottom portion 38 of said deflector. Said deflecting wall extends from the advance side of the machine rearwardly inwardly towards the center thereof along one side or end of the conveyer 10, depending upon the position of said conveyer, and with said trough-like bottom portion is arranged to elevate and deflect the cuttings onto the receiving end of said conveyer when said conveyer is in either a longitudinal or laterally extended position with respect to the machine.

The detachable connection from said conveyer frame 29 to the rear end of the machine, to permit said conveyer frame to be connected in cuttings receiving relation with respect to said deflector when extending rearwardly or laterally of the machine, includes an angle 39, one leg of which may be secured to a rear end portion of the rear wall 37, and the other leg of which may extend rearwardly from said rear wall and be secured to a side wall 40 of said conveyer frame in a suitable manner, as by nuts and bolts. The other side of said conveyer may be attached to the retreating rear end of the machine by means of a connecting member 43, connected to an ear 44 projecting laterally from the frame of the mining machine. Said connecting member is secured to a front end wall (not shown) of said conveyer frame by means of suitable nuts and bolts.

When it is desired that the conveyer extend laterally with respect to the machine, to permit operation in places where the props are posted close to the working face, a connecting strap 45 is substituted for the angle 39 and is connected

between the side wall 40 and the rear end portion of the wall 37 of the deflecting member 35. The connecting member 43 is connected between the ear 44 and the side wall of the conveyer opposite from the strap 45 (see Figure 3). Said conveyer is so located with respect to said deflecting member that the cuttings will be deflected thereto when extended laterally or longitudinally rearwardly from the machine, the top surface thereof being on a level with the bottom deflecting surface of said cuttings deflecting member.

A cuttings channel generally indicated by reference character 47 extends along the advance side of the cutter bar on the top side of the base plate 15 and leads to the portion 38 of the deflector 35. Said cuttings channel includes a member 48 of a U-shaped formation having sides inclined upwardly from said base and extending along opposite sides of the cutter bar 13 and around the sprocket 16 and disposed beneath said cutter bar and sprocket. Said inclined sides extend upwardly from said base plate at an inclination substantially parallel to the plane of inclination of the bottom block of the cutter chain (see Figure 4). The opposite side of said channel is formed from an inclined cuttings guiding member 49, inclined at an angle opposite from the angle of inclination of the member 48. Said member extends along the advance side of the machine along one side wall thereof, and is spaced laterally from the member 48 a distance sufficient to provide a substantially V-shaped channel leading to the rear end of the machine and terminating into the trough-like bottom portion 38 of the deflector 35 and the laterally extending portion 36 of said deflector. Thus, when the machine is cutting across a coal face, the cuttings discharged by the cutter chain are propelled by the cutter chain along the channel 47 formed by the inclined members 48 and 49 to the trough-like portion 38 and upwardly along the curved deflecting surfaces of the deflecting member 35 onto the receiving end of the elongated frame 29 of the conveyer, when said conveyer extends longitudinally or rearwardly of the machine.

Referring now in particular to the improved form of drive from the mining machine motor 13 to the slack removing conveyer 10, the longitudinal shaft 21, as herein shown, is provided with a rearward extension 50, having spaced bearings 51 and 52 thereon and carried within opposite ends of a housing member 53, projecting rearwardly from the rear portion of the machine frame and adjustably movable about the axis of said shaft on said bearings. A sleeve 54, having a bevel gear 55 keyed thereto, is journaled on said shaft and is adapted to be selectively connected thereto by means of a suitable clutch, herein shown as being a usual form of jaw clutch 57. Said clutch includes a clutch collar 58, feathered on said extension of said shaft and having clutch jaws 59 on one face thereof, adapted to be selectively engaged with clutch jaws 60 on the sleeve 54. Said clutch is operated by a suitable shifting mechanism of a well-known form and construction and not herein shown or described in detail since it is no part of my present invention.

The bevel gear 55 meshes with and drives a bevel gear 63, journaled on its hub in a wall 64 of the housing 53. As herein shown, a bevel pinion 65 on the end of a shaft 66, keyed to the hub of said bevel gear, meshes with and drives a bevel gear 67 keyed to a longitudinally extending shaft 69. Said last mentioned bevel gear

is journaled on its hub in a housing and turning frame 70 and said shaft is journaled at its end opposite from said bevel gear in said housing and frame. The end of said shaft adjacent said gear projects rearwardly from said housing and turning frame and has driving connection with an inclined extensible shaft 73, by means of a universal coupling 74, of a usual construction.

The housing and turning frame 70 has an inner flanged portion 75 which is guided in an annular guide 76 formed in the housing 53, and said flanged portion is retained in said guide by means of a split annular ring 77, so said housings may be adjustably moved with respect to the drive shaft 21 about perpendicular axes. When the conveyer is positioned to extend rearwardly of the frame 12, the housing 53 is pivoted about the axis of the shaft 21, to dispose the housing 70 towards the advance side of the machine, as in Figures 1 and 8; and when the conveyer is positioned to extend laterally from the machine, the housing 53 is turned about the shaft 21 to an upright position, the housing 70 being positioned at an angle thereto about a vertical axis, as shown in Figure 9, so that the conveyer may be driven from the motor 48 in any desired position of horizontal adjustment with respect thereto.

The drive from the extensible shaft 73 to the conveyer is shown in detail in Figure 7 and includes a universal coupling 79 having driving connection with the forward end of a longitudinally extending shaft 80 journaled in a frame 81. Said frame is provided with an annular flanged inner portion 82, guided within an annular guide formed in a member 84, which is secured to an outer side wall 40 of the frame 29 and projects outwardly therefrom. An annular ring 85 is provided to retain said frame in said annular guide so said frame may move about the axis of a conveyer drive shaft 86 journaled therein. A bevel pinion 87 keyed on the shaft 80 meshes with and drives a bevel gear 88 on said conveyer drive shaft 86. Said drive shaft has the usual sprockets 89, 89 mounted thereon which mesh with and drive the conveyer chains 32, 32 and flights 33, 33 along the elongated frame 29.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a kerf-cutting machine of the room and pillar type, a frame having a cuttings passageway extending therethrough, a cutter bar projecting from and extending within said frame and a cutter chain guided for movement about said cutter bar and about a drive sprocket at the rear end of said frame, said cuttings passageway terminating into a deflecting member having a portion extending across the rear end of said passageway and another portion extending rearwardly beyond the rear end of the machine adjacent the advance side thereof, the inner margins of said portions forming a substantially rectangular recessed portion at the rear of said cuttings passageway, and a cuttings removing conveyer adapted to extend laterally of or rearwardly from the rear end of the machine and to ex-

tend within said recessed portion of said deflecting member in cuttings receiving relation with respect thereto when in either a rearwardly or laterally extended position.

2. In a kerf-cutting machine of the room and pillar type, a frame having a cuttings passageway extending therethrough, a cutter bar projecting from and extending within said frame and a cutter chain guided for movement about said cutter bar and about a drive sprocket at the rear end of said frame, said cuttings passageway terminating into a deflecting member having a portion extending across the rear end of said passageway and another portion extending rearwardly beyond the rear end of the machine adjacent the advance side thereof, the inner margins of said portions forming a substantially rectangular recessed portion at the rear of said cuttings passageway, a cuttings removing conveyer adapted to extend laterally of or rearwardly from the rear end of the machine and to extend within said recessed portion of said deflecting member in cuttings receiving relation with respect thereto when in either a rearwardly or laterally extended position, means for detachably connecting one portion of said conveyer to the rear portion of said rearwardly extending portion of said deflecting member, and other means for detachably connecting another portion of said conveyer to the rear end of the machine, for holding said conveyer in cuttings receiving relation with respect to said deflecting member when in a longitudinal or laterally extended position with respect to said frame.

3. In a kerf-cutting machine of the room and pillar type, a frame having a cuttings passageway extending therethrough, a cutter bar projecting from and extending within said frame and a cutter chain guided for movement about said cutter bar and about a drive sprocket at the rear end of said frame, said cuttings passageway being of a trough-like formation and extending beneath and along the advance side of said cutter bar and having said cutter chain movable along the bottom thereof, to progress the cuttings rearwardly therealong, said passageway terminating into a deflecting member having a portion extending rearwardly from the advance side of the machine and another portion extending across the rear end of said cuttings passageway, and a cuttings removing conveyer adapted to be connected to the machine in cuttings receiving relation with respect to both portions of said deflecting member, so said deflecting member will deposit material on two sides of said conveyer.

4. In a kerf-cutting machine of the room and pillar type including a frame having a cuttings passageway extending therethrough, a cutter bar projecting from and extending within said frame and a cutter chain guided for movement about said cutter bar and about a drive sprocket at the rear end of said frame, said cuttings passageway being of a trough-like formation and extending beneath and along the advance side of said cutter bar and having said cutter chain movable along the bottom thereof, to progress the cuttings rearwardly therealong, said passageway terminating into a deflecting member having a portion extending rearwardly from the advance side of the machine and another portion extending across the rear end of said cuttings passageway, and a cuttings removing conveyer adapted to be detachably connected to the machine to extend rearwardly from the rear end.

thereof or laterally beyond the retreating side thereof in cuttings receiving relation with respect to both portions of said deflecting member, so said deflecting member will deposit material onto two sides of said conveyer when in either a rearwardly or laterally extended position with respect thereto.

5. In a kerf-cutting machine of the room and pillar type, a frame having a cuttings passageway extending therethrough, a cutter bar projecting from and extending within said frame and a cutter chain guided for movement about said cutter bar and about a drive sprocket at the rear end of said frame, said cuttings passageway being of a trough-like formation and extending beneath and along the advance side of said cutter bar and having said cutter chain movable along the bottom thereof, to progress the cuttings rearwardly therealong, said passageway terminating into a deflecting member having a portion extending rearwardly from the advance side of the machine and another portion extending across the rear end of said cuttings passageway, a cuttings removing conveyer including a relatively horizontal receiving portion and an inclined discharge portion, and means for detachably connecting the receiving portion of said conveyer to said kerf-cutting machine so it may be positioned to extend longitudinally rearwardly of or laterally from said cuttings passageway and be in cuttings receiving relation with respect to both portions of said deflector, when in either of these positions.

6. In a kerf-cutting machine of the room and pillar type, a frame having a cuttings passageway extending therethrough, a cutter bar projecting from and extending within said frame and a cutter chain guided for movement about said cutter bar and about a drive sprocket at the rear end of said frame, said cuttings passageway being of a trough-like formation and extending beneath and along the advance side of said cutter bar and having said cutter chain movable along the bottom thereof, to progress the cuttings rearwardly therealong, said passageway terminating into a deflecting member having a portion extending rearwardly from the advance side of the machine and another portion extending across the rear end of said cuttings passageway, a cuttings removing conveyer including a relatively horizontal receiving portion and an inclined discharge portion, and means for detachably connecting the receiving portion of said conveyer to said kerf-cutting machine so it may be positioned to extend longitudinally rearwardly of or laterally from said cuttings passageway and be in cuttings receiving relation with respect to both portions of said deflector, when in either of these positions, including means for connecting one portion of said conveyer with the rear end of said rearwardly extending portion of said deflector, and other means for connecting another portion of said conveyer with said cutting machine.

7. In a kerf-cutting machine of the room and pillar type, a frame having a cuttings passageway extending therethrough, a cutter bar projecting from and extending within said frame and a cutter chain guided for orbital movement about said cutter bar, a sprocket at the rear end of said frame for driving said cutter chain about said cutter bar, a cuttings removing conveyer adapted to be connected to said kerf-cutting machine to extend longitudinally rearwardly of or laterally from the rear end of said machine,

5 said conveyer including an inclined frame having a transversely extending drive shaft at the rear end thereof, and means driven by the motor of said machine for driving said shaft when said conveyer is in either a longitudinally or laterally extended position with respect to said machine including a longitudinally extending shaft journaled in the frame of said machine and driven from the motor thereof, a housing on said shaft and adjustable about the axis thereof, another housing mounted on said housing for adjustable movement about an axis perpendicular to the axis of said longitudinal shaft, a shaft journaled in said second housing for rotation about an axis parallel to the axis of rotation of said longitudinal shaft, geared drive connections in said housings for driving said second shaft from said longitudinal shaft in all positions of said housings with respect to each other, and a universal extensible drive connection between said second shaft and said transverse shaft.

8. In a kerf-cutting machine of the room and pillar type, a frame having a cuttings passageway extending therethrough, a cutter bar projecting from and extending within said frame and a cutter chain guided for orbital movement about said cutter bar, a sprocket at the rear end of said frame for driving said cutter chain about said cutter bar, a cuttings removing conveyer adapted to be connected to said kerf-cutting machine to extend longitudinally rearwardly of or laterally from the rear end of said machine and including an inclined frame having a transversely extending drive shaft at the rear end thereof, and means driven by the motor of said machine for driving said conveyer when in either a longitudinally or laterally extended position with respect to said machine including a longitudinally extending shaft journaled in said machine and driven from the motor thereof, a housing adjustable about the axis of said shaft, another housing mounted on said housing for pivotal movement about an axis perpendicular to the axis of said longitudinal shaft, a shaft journaled in said second housing and rotatable about an axis parallel to the axis of said longitudinal shaft, geared drive connections in said housings for driving said second shaft from said first shaft in all positions of adjustment of said housings with respect to each other, and a universal extensible drive connection between said second shaft and said transverse conveyer drive shaft, said universal extensible drive connection including a housing mounted on said conveyer frame for movement about an axis coaxial with said transverse shaft and bevel gearing carried by said housing and connecting said extensible drive connection with said transverse shaft.

9. In a kerf-cutting machine of the room and pillar type, a frame having a cuttings passageway extending therethrough, a cutter bar projecting from and extending within said frame and a cutter chain guided for orbital movement about said cutter bar, a sprocket adjacent the rear end of said frame, for driving said cutter chain about said cutter bar, a cuttings removing conveyer adapted to be connected to the rear end of said frame, to carry away the cuttings discharged through said passageway, said cuttings passageway including a cuttings channel of a trough-like formation extending along the bottom of said frame and within which certain bits of the cutter chain extend, said channel being close to said cutter bar and curving at the rear end of said frame to conform to the path of the cutter chain,

as it passes around said sprocket, and leading into a deflecting member having one portion extending beyond the rear end of the machine adjacent the advance side thereof for deflecting the cuttings onto one side of said conveyer and having another portion extending across the rear end of said passageway in advance of said conveyer, for deflecting the cuttings onto another side of said conveyer.

10. In a kerf-cutting machine of the room and pillar type, a frame having a cuttings passageway extending therethrough, a cutter bar projecting from and extending within said frame and a cutter chain guided for orbital movement about said cutter bar, a sprocket adjacent the rear end of said frame for driving said cutter chain about said cutter bar, a cuttings removing conveyer adapted to be connected to the rear end of said frame, to carry away the cuttings discharged through said passageway, said cuttings passageway including a cuttings channel of a trough-like formation extending along the bottom of said frame and within which certain bits of the cutter chain extend, said channel being close to said cutter bar and curving at the rear end of said frame to conform to the path of the cutter chain as said cutter chain passes around said sprocket, and said cuttings channel leading into a deflecting member arranged to deflect the cuttings onto two sides of said conveyer and having a portion extending along one side of said conveyer beyond the rear end of the machine adjacent the advance side thereof and having another portion

forming a gradually inclined rear wall of said channel and extending across the rear end of said frame in advance of said conveyer, for elevating the cuttings onto said conveyer.

- 5 11. In a kerf-cutting machine of the room and pillar type, a frame having a cuttings passageway extending therethrough, a cutter bar projecting from and extending within said frame and a cutter chain guided for movement about said cutter bar, a cutter chain drive sprocket adjacent the rear end of said frame, said cuttings passageway including a cuttings channel of a trough-like formation extending along the bottom of said frame and within which certain bits of the cutter chain extend, said channel being close to said cutter bar and conforming to the path of said cutter chain as it passes around said sprocket and leading into a deflecting member having a vertically extending wall portion extending rearwardly from the advance side of the machine and another portion extending across the rear end of said cuttings passageway and having a portion forming a gradually inclined rear wall of said channel, to permit the cuttings to be propelled therealong and elevated thereby over the top of said deflector, and a cuttings removing conveyer adapted to be connected to the machine in cuttings receiving relation with respect to both portions of said deflecting member, so said deflecting member will deposit material onto two sides of said conveyer.
